United States Patent Office.

HENRY EVERDELL, OF NEW YORK, N. Y.

Letters Patent No. 64,753, dated May 14, 1867.

ENVELOPE.

The Schedule referred to in these Letters Patent and making part of the same.

TO ALL WHOM IT MAY CONCERN:

Be it known that I, HENRY EVERDELL, of the city, county, and State of New York, have invented a certain new and useful improvement in Envelopes, of which the following is a full, clear, and exact description reference being had to the accompanying drawing, forming part of this specification, and in which—

Figure 1 represents a rear view of an envelope constructed according to my improvement.

Figure 2, a transverse section of the same; and

Figure 3 a rear view of a similarly constructed envelope, but modified in shape.

Like letters indicate like parts throughout the several figures.

This improvement relates to what are known as card or wedding envelopes, in which the flap of the envelope is usually left open or unsealed, and my invention consists in providing the one wing or portion of the back of the envelope with an incision into which the tongue of the loose wing or flap is made to fit, and so embossing such two connecting portions, and furnishing said flap with a bow or knot of ribbon, as that while the envelope is kept shut, but in a manner that readily admits of it being opened without tearing the flap by simply drawing the tongue out of the incision in the back, said tongue appears to project through a strap in the back, and as if tied by the bow, thereby giving a neat and ornamental finish to the envelope with protection against flaring open, and yet having all the advantage and convenience of an open envelope.

Referring to the accompanying drawing, A represents the loose or open flap of the envelope, and a its tongue, which, in closing the envelope, is projected through an incision, b, into, within, or under the back wing B, that is embossed on the outside, as at c c, with a figure corresponding to the shape of the tongue and embossing d on the tongue and flap, and which back is further embossed with a figure or lines, e e, resembling a cross-strap, the whole giving to the tongue the appearance of its being projected through a cross-strap, while a bow or knot, C, that may be of satin ribbon, on the tongue or flap above the imitation strap, gives a tied or knotted aspect to the flap, which, though the insertion of its tongue within the incision b keeps the envelope from flaring open, is nevertheless free to be opened without tearing, unsealing, or untying, by simply drawing the tongue a out of the incision b. The deception of the envelope's lock or tie by the bow C will restrain its being opened by many not warranted to do so. Of course the shape of the wings and flap, with its tongue and lines or figures embossed on it, may be varied at pleasure. In figs. 1 and 2 the opening flap is shown as running the width of the envelope, and in fig. 3 as opening endwise.

What I claim as my invention, and desire to secure by Letters Patent, is—

The envelope, constructed substantially as described, with a flap and tongue, the latter fitting through an incision in a closed wing or portion of the back, and the tongue or flap and wing into which it fits being embossed and provided with a bow or knot to give a secured aspect to the envelope, while it is left free to open, yet protected against flaring open, substantially as specified.

HENRY EVERDELL.
